EMERGENCY UMBRELLA AND THE LIKE

Samuel Ruskin and Roy Dermack, Brooklyn, N. Y.

Application December 15, 1948, Serial No. 65,322

1 Claim. (Cl. 135—19.5)

1

This invention relates to new and useful improvements in emergency umbrellas, novelty shields, and similar articles.

More particularly, the invention contemplates an exceptionally inexpensive article as mentioned which is suitable for distribution among persons congregated indoors or outdoors, as at fairs, races, athletic events, theatres, indoor sports, meetings, etc. It is contemplated that the articles be suitable for sale, or as advertising premiums. They may also be sold at five and ten cent stores, or other stores, and through vending machines.

An important object of this invention is to construct the emergency umbrella, novelty shield, or other similar article so that it may be fabricated of relatively lightweight cardboard, Bristol board or similar material. The top face, or both faces, of these materials may be water-proofed, or the materials themselves may be of semi-rigid water-proof sheet material.

It is another object of this invention to make use of a covering sheet in the article which is adapted to be held overhead when the article is used as an umbrella, or to constitute the shield proper when the article is used as a novelty shield. It is proposed that this covering sheet be provided with a fold so that it may be folded to reduce the size of the article for carrying or storage purposes.

An important and dominating feature of the invention resides in a particular arrangement of the fold in the covering sheet, and a particular combination of handles for supporting the covering sheet with the fold of the covering sheet. It is contemplated that the handles be constructed of the same or similar material to the covering sheet, namely, semi-rigid sheet material. It is an object of this invention to so arrange the fold and the handles so that the handles receive compression stresses due merely to the weight of the covering sheet and take tensional stresses due to the resiliency of the folded sheet and due to winds. This arrangement is important because semi-rigid material of light weight cannot take much compression in that it will bend, but in tension it can take much greater loads.

It is proposed to accomplish the objects mentioned in the previous paragraph by arranging the covering sheet with a central fold which extends downwards and dividing the sheet into two leaves which tend to fold upwards towards and against each other. It is proposed that the semi-rigid handles be attached to the bottom faces of the leaves near the central fold so that

2

the handles may be brought together and held in one hand to support said covering sheet in a substantially flat condition in order that stresses due to the tendency of said leaves to fold upwards caused by inherent resiliency and winds, are communicated to said handles as tensional stresses.

Another object of the invention is the construction of a device as described which is simple and durable and which may be manufactured and sold at a low cost.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

20 Fig. 1 is a plan view of an emergency umbrella or novelty shield constructed in accordance with this invention.

Fig. 2 is a front elevational view of Fig. 1.

Fig. 3 is a fragmentary enlarged elevational view looking in the direction of the line 3—3 of Fig. 2.

Fig. 4 is an enlarged front elevational view of the article in a folded condition.

Fig. 5 is a fragmentary enlarged front elevational view of an emergency umbrella or novelty shield constructed in accordance with a modified form of this invention.

Fig. 6 is an elevational view looking in the direction of the line 6—6 of Fig. 5.

Fig. 7 is a fragmentary transverse sectional view of an emergency umbrella or novelty shield embodying still another form of this invention.

The emergency umbrella, novelty shield, or the like, in accordance with that form of the invention illustrated in Figs. 1—4 inclusive, includes a top horizontal semi-rigid covering sheet 10 having a central fold 11 which extends downwards dividing the sheet 10 into leaves 12 and 13 which tend to fold upwards and against each other and which may be folded together as illustrated in Fig. 4, to reduce the size of the umbrella or novelty shield. A semi-rigid handle 14 is attached to the bottom face of each of said leaves 12 and 13 near said central fold 11 so that the handles 14 may be brought together and held in one hand to support said covering sheet 10 in a substantially open flat condition in order that stresses due to the tendency of said leaves to fold upwards caused by inherent resiliency of the covering

sheet 10 and winds, are communicated to said handles 14 as tensional stresses.

Each handle 14 has a top flange 15 attached to said covering sheet 10 with glue or wire stitches, and a shank portion 16 depending downwards from said flange portion 15. A fold 17 is arranged between said flange 15 and said shank 16, and said fold 17 is arranged parallel to the fold 11 in order that stresses due to the tendency of said leaves 12 and 13 to fold upwards which are communicated to said fold 17 is distributed along the length of the fold 17. If the fold 17 was at an angle to the fold 11 stresses would be communicated to one end of the fold 17, and as the fold 17 tore, stresses would run along the fold 17 to the other end causing the fold 17 to rip completely.

The handles 14 are provided with openings 18 through which the fingers of the hand may be engaged.

The operation and use of the emergency umbrella or shield may be understood from the following:

Normally, when the umbrella is not in use, as illustrated in Fig. 4, the leaves 12 and 13 are folded up and against each other and the shank portions 16 of the handles 14 are also folded upwards and against the faces of the leaves 12 and 13.

The umbrella or shield is used by folding the leaves 12 and 13 downwards so that the sheet 10 is flat and then supporting the sheet 10 by engaging the fingers of one hand through the openings 18 of the handle 14. The umbrella may be supported over one's head for protection against rain and snow, or it may be supported in front of a person as a novelty shield during play.

It should be particularly noted that the handles 14 are required to support the weight of the sheet 10. This weight acts as a compression force upon the handles 14. Forces due to the tendency of the sheet 10 to fold closed caused by the inherent resiliency of the sheet 10, or by winds, are communicated to the handles 14 as tensional forces. For this reason the handles 14 may be of relatively lightweight semi-rigid material.

In Figs. 5 and 6, a modified form of the invention has been disclosed which distinguishes from the prior form merely in the construction of the handles 20. Each handle 20 is provided with a top flange portion 21 which is attached to the cover sheet, and a shank portion 22. These shank portions 22 are formed so that the grain of the cardboard or other material facilitates rolling the shank portions 22 together into conical form, as illustrated on the drawing. The shank portions 22 may be formed with score lines 23 to facilitate rolling said shank portions into the conical shape shown. The covering sheet is easily supported by the conical shaped handles 20. The conical shaped handles 20 are convenient to be gripped. They are stronger than the handles shown in the prior form of the invention as there are no cutout portions which would weaken the handles. Moreover, a conical shape is a stronger structural shape than the flat shape of the handles in the prior form of the invention. The dot and dash lines 20 indicate the handles before they are rolled into the conical shape.

In other respects this form of the invention is identical to the previous form and like parts are identified by like reference numerals.

In Fig. 7 still another modified form of the invention is disclosed which distinguishes from the prior forms in the construction of the handle for the covering sheet. More specifically, the covering sheet is provided with a handle 25 formed from a strip of semi-rigid material which is bent into the triangular shape shown on the drawing. The ends 26 of the strip of material forming the handle are adjacent each other at the top and are attached to each other and to the material of the covering sheet. The sides of the handle are formed with openings 27 for the fingers of one hand to engage through. When the covering sheet is folded the handle 25 will also fold.

It is pointed out that paid advertisements, or premium advertisements or decorative designs may be imprinted upon the various sheets forming the article.

While we have illustrated and described the preferred embodiments of our invention, it is to be understood that we do not limit ourselves to the precise constructions herein disclosed and the right is reserved to all changes and modifications coming within the scope of the invention as defined in the appended claim.

Having thus described our invention, what we claim as new and desire to secure by United States Letters Patent is:

In an emergency umbrella, novelty shield, or the like, a top horizontal semi-rigid covering sheet having a central fold which extends downwards dividing the sheet into two leaves which tend to fold upwards towards and against each other, and a semi-rigid handle attached to the bottom face of each of said leaves near said central fold so that the handles may be brought together and held in one hand to support said covering sheet in a substantially flat condition in order that stresses due to the tendency of said leaves to fold upwards are communicated to said handles as tensional stresses, each of said handles having a flange portion attached to said covering sheet, a shank portion depending downwards from said flange portion, and a fold between said flange and shank portions, and said last named fold being parallel to said first named fold in order that stresses due to the tendency of said leaves to fold upwards which are communicated to said last named folds are distributed along the lengths of the last named folds.

SAMUEL RUSKIN,
ROY DERMACK.
